UNITED STATES PATENT OFFICE.

GEORGE A. BROCKWAY, OF ST. PAUL, MINNESOTA.

CUE TIP.

Application filed January 20, 1921. Serial No. 438,787.

To all whom it may concern:

Be it known that I, GEORGE A. BROCKWAY, a citizen of the Dominion of Canada, residing at St. Paul, in the county of Ramsey and State of Minnesota, have invented certain new and useful Improvements in Cue Tips, of which the following is a specification.

This invention relates to cue tips for use in propelling billiard balls and the like, the principal object of my invention, being the provision of an improved cue tip construction, whereby I effectuate the long desired result of preventing the tip proper, from becoming separated (due to the severe blows it receives) from its associated parts, usually employed in the construction of this class of devices.

A further object of my invention, is to provide, in a device of the class described, a certain uniformity of proportion of interfitting parts, whereby to facilitate assembling thereof.

A still further object of the invention is to provide an improved, simple, and effective means for firmly holding the tip positioned against rotary, as well as longitudinal movement with respect to the body of the cue, said holding means including provision, whereby the tip proper, may be easily removed and positioned anew in a different circumferential position relative to the body of the cue.

In the accompanying drawings forming part of this specification:

Figure 1 is a side view of the upper portion of a billiard cue.

Figure 2 is a vertical longitudinal section of Figure 1.

Figure 3 is a vertical sectional view taken at right angles to Figure 2.

Figure 4 is an enlarged fragmentary sectional view showing the connecting member as it appears when driven home.

Figure 5 is an enlarged perspective view of the connecting member.

Figure 6 is a perspective view of the upper portion of the connecting member, showing it as it appears before it is driven into the holding position.

Figure 7 is a plan view of the ferrule, and

Figure 8 is a plan view of the washer.

A designates the body of the cue, and B a reduced part thereof of uniform diameter to form a dowel. C designates the ferrule having a bore 1, adapted to frictionally receive the dowel B of the cue, so that when

the ferrule is driven thereover, the outer diameter of the ferrule and cue will present a smooth flush surface. Centrally, in longitudinal alignment with the bore 1, is the rectangular opening 2, that shown being of equal sides so as to form a square. Seated on the upper flat end of the ferrule is the fiber washer 3, said washer being comparatively thin and preferably made of vulcanized fiber or other tough material. Centrally, in alignment with the opening 2 and the bore 1, the washer is formed with an oblong rectangular opening, adapted to receive the prongs 4 of the connecting member D, when said prongs are positioned as shown in Figure 6 of the drawings. The connecting member D, is formed of a strap of metal, cut to a width so as to slidably fit widthwise into the opening 2, and lie flatly against any of the walls thereof. The strap is bent upon itself, to form an oblong loop 5, having flat outer parallel sides 6, said sides being bent inwardly so as to bring the upper ends forming the prongs 4, flatly against each other. The upper free ends of the prongs, are beveled inwardly toward each other to form inclined surfaces 7. The edges of the metal strap are formed near the upper end of the prongs, with acutely angled shoulders or spurs 8, after the manner of the spurs of a fish hook, the edges of the strap being inclined upwardly and inwardly thereby giving the prongs the appearance of arrow heads. The fiber washer, is formed centrally with a central flat bottomed recess 9, adapted to receive the washer 10, the latter also having a central rectangular opening 11, coinciding with the opening in the fiber washer. Thus, the washer 10 may be inserted in the recess 9, so as to be flush with the top surface of the fiber washer. The washer 10, is preferably made of soft metal such as brass or the like. Secured to the top of the washer and covering its entire upper surface, is the cue tip proper 12, preferably made of leather or other fibrous material. The tip proper, is suitably secured to the fiber washer as by glue or other means to form a permanent joint therebetween thereby forming what may be termed a tip made of two sections, the fiber washer constituting a base.

Referring again to Figure 5 of the drawings, the loop 5 fits frictionally with its side 6, into the opening 2, the curved ends 13 of the loop imparting a certain resiliency

or spring to the loop to permit the latter to be crowded under stress into the opening 2, by force, so as to frictionally hold it therein. Obviously, the loop may be inserted in the 5 opening 2 of the ferrule, in any one of two positions, as the opening 2 is square in cross section. The tip and its washer 3 may be removably attached to the top of the cue in the following manner. The connecting 10 member is first driven into the tip formed by the fiber washer and the leather member 12. This is accomplished by a special machine, so that the loop 5 projects from the under surface of the fiber washer 3. The 15 tips are placed upon the market in this form. They are secured to the ferrule by disposing the rounded end of the loop 5 into the opening 2, and gently driving the tip downwardly from above.

20 In the machine the prongs are driven into the body of the leather, the inclined faces 7 thereof causing them to divergently separate laterally as they enter the leather. The inclined sides 14 of the spurs 8, having pushed 25 the fibers of the leather out of the way in their travel, and the latter then having permitted said fibers to a degree, to assume their normal positions back of the spurs 8, the prongs are now firmly anchored in the 30 fibrous body of the leather.

In the United States Patent No. 1,307,922, June 24, 1919, assigned in part to me, the prongs were not provided with the spurs 8, as in the present invention. It has been

35 found, that the constant pounding on the end of the tip proper, causes the prongs, in the absence of the spurs 8, to back out of the leather and thereby split the washer 3 diametrically through its rectangular opening, 40 causing the tip proper to become loosened from the end of the cue. By constructing the prongs as shown, I have found that the connecting member does not back out of the leather and thereby effectively prevents 45 splitting of the washer 3.

To further safe-guard the splitting of the washer 3, I have added the washer 10, whereby the outwardly flaring under sides 15 of the prongs will be engaged by the 50 edges of the opening 11, thereby preventing

said flaring sides from wedging the washer asunder. As the fiber washer is quite thin, the metal washer must be made of very thin metal to prevent the recess from cutting through, the thin metal easily tearing at the 55 corners of the opening 11 so that the washer alone cannot always be relied upon. To replace the tip, the latter may be gripped bodily with pliers and pulled out of the socket 2 in the ferrule, and replaced with 60 another. If, however, a tip for some reason becomes loosened it may be withdrawn in the manner just described, when the sides 6 of its loops 5 will spring outwardly to a degree approaching its normal position, or, 65 in other words will widen a trifle as it is removed from the socket. It may now be turned a quarter turn, so that the walls 6 thereof will engage two new faces in the opening 2, and be firmly frictionally held 70 endwise when driven home. As the walls, of the squared opening 2 originally are more or less rough, (the ferrule being usually made of fiber pyrolin or other similar material) the new sides engaged by the resetting of the cue tip, grip anew the sides 6 of the connecting member, so that it will practically constitute a new connection. The capability of doing this extends the life of 75 the cue tip. In the patent above mentioned, 80 the loop was wider than it was thick, so that when the cue tip was once worn loose, a new tip proper had to be provided.

I claim:

A cue tip comprising a ferrule secured 85 upon the end of a cue, a tip member disposed upon the outer end of said ferrule, a spring member extending from said tip member and frictionally engageable within the ferrule recess, the transverse edge extremities of the ends of the spring member being beveled inwardly toward each other whereby the ends will extend divergently when driven into the tip member, each diverging end of said spring member being 90 formed with a spear-like head having a pair of lateral sharp spurs directed divergently toward the ferrule and undercut.

In testimony whereof I affix my signature.
GEORGE A. BROCKWAY.
